W. J. McCABE,
CLOTHES LINE SUPPORT,
APPLICATION FILED OCT. 7, 1915.

1,176,578.

Patented Mar. 21, 1916.

UNITED STATES PATENT OFFICE.

WILLIAM J. McCABE, OF NEW YORK, N. Y.

CLOTHES-LINE SUPPORT.

1,176,578.

Specification of Letters Patent. Patented Mar. 21, 1916.

Application filed October 7, 1915. Serial No. 54,572.

To all whom it may concern:

Be it known that I, WILLIAM J. McCABE, a citizen of the United States, residing at New York, in the county of New York and 5 State of New York, have invented certain new and useful Improvements in Clothes-Line Supports; and I do hereby declare the following to be a full, clear, and exact description of the invention, such as will enable others skilled in the art to which it 10 pertains to make and use the same.

My invention relates to new and useful improvements in clothes line supports and more particularly to that class adapted to be 15 suspended from a post, building, or similar object, and my object is to provide a plurality of clothes line sections and movably mount the same on supporting arms.

A further object is to so arrange said arms 20 that they may be folded into compact form around a supporting rod.

A further object is to provide a combined supporting bracket and housing for the supporting rod and arms.

25 Other objects and advantages will be hereinafter set forth and more particularly pointed out in the accompanying specification.

In the accompanying drawings which 30 are made a part of this application, Figure 1 is a perspective view showing the clothes lines and supporting means therefor in operative position by full lines and in folded position by dotted lines, and Fig. 2 is a sectional view through the outer end of the supporting bracket, showing the line supports in folded position.

Referring to the drawings in which similar reference numerals designate corresponding 40 parts throughout the several views, 1 indicates a window frame of a building, to the outer face of which is attached a hinge member 2 to which is pivotally attached a head 3 for the support of the line supporting 45 bracket 4, said bracket being preferably channel shaped, as best shown in Fig. 2 to form a housing, the lower side of the bracket being open. The bracket 4 is pivotally attached to the head 3 by means of a pin 5, 50 said pin extending through an elongated slot 6 in the head 3 so that the bracket may be moved longitudinally of the head to engage tongues 7 at the inner ends of the side

walls of the bracket with studs 8 on the head 3 or to disengage the tongues therefrom. 55

The tongues 7 are so positioned on the side walls of the bracket that when in engagement with the studs 8 the bracket 4 will be held in horizontal position, but when the bracket is moved outwardly the full length 60 of the slot 6 the tongues will swing clear of the studs 8 and permit the bracket to swing downwardly to a vertical position as shown by dotted lines in Fig. 1.

Pivottally attached between the side walls 65 of the bracket and adjacent the outer ends thereof is a swivel head 9 to which is swivelly attached a supporting rod 10, the opposite end of said rod having a collar 11 fixed thereto in which are formed a plurality of channels 12 to receive the ends of the line supporting arms 13, said arms being pivotally secured in said channels. 70

Attached to one face of each arm, adjacent the inner and outer ends thereof, are 75 sheaves 14 around which are mounted endless lines 15 for the reception of garments, said lines being longitudinally movable so that the garments may be attached to the line adjacent the outer end of the arm and 80 moved to a position adjacent the inner end thereof by moving the line lengthwise.

When the lines are not in use, the arms are folded parallel with the supporting rod 10 and secured in their folded position by 85 means of a sleeve 16 slidably mounted upon the supporting rod, the flange of the sleeve surrounding the free ends of the arms and securely holding them in folded position.

After the arms are secured by the sleeve 90 16, the supporting rod may be swung upwardly and housed within the bracket 4. A latch 17 engages the collar 11 and holds the supporting rod against swinging motion. The bracket 4 may then be swung to a vertical position as shown by dotted lines in 95 Fig. 1, thereby disposing the support in close proximity to the wall of the building or window frame.

In applying the device to use, the bracket 100 4 is first swung to a horizontal position and then moved inwardly until the tongues 7 pass below the studs 8, thus holding the bracket in rigid horizontal position but permitting the same to swing laterally in view 105 of the hinged connection of the head 3 with

the hinge member 2. The latch 17 is then disengaged from the collar 11 which will permit the supporting rod 10 to swing to a vertical position when the bracket 4 is 5 swung laterally toward the window and thus bringing the sleeve 16 into reach of the operator so that said sleeve may be elevated and the arms 13 released when said arms will swing by gravity to a horizontal 10 position, the channels 12 being so arranged as to limit the downward swinging movement of the arms. The bracket 4 is then moved laterally until the end of one of the 15 arms is in juxtaposition to the window when the garments to be dried are placed upon the line upon that particular arm and as the line can be moved lengthwise the operator is not required to lean out of the window in order to engage the garment 20 with the line adjacent the end thereof attached to the collar, as by moving the line lengthwise around the sheaves, the first garment attached to the line may be moved to the inner end of the arm.

25 It will likewise be seen that by swivelly attaching the supporting rod 10 to the swivel head 9, said rod and arms carried thereby may be rotated to successively bring the ends of the arms before the window to receive the garments to be dried.

It will likewise be seen that when the device is not in use, it can be folded into very compact form and disposed in close position to the object to which it is attached and is 30 designed primarily for use in large cities where space is limited or upon tall buildings.

Having thus fully described my invention what I claim as new and desire to

secure by Letters Patent of the United States is:—

1. A clothes line support, comprising a hollow bracket, means to pivotally attach the bracket to an object, means to hold the bracket in horizontal position, a swivel head pivoted to one end of the bracket, a supporting rod swivelly attached to said head, arms pivoted to said rod, endless lines movably secured to said arms, and means to hold the arms in folded position. 40

2. A clothes line support, comprising a hollow bracket, a head pivoted to the inner end of the bracket, means to pivotally attach the head to an object, studs carried by the head, tongues on the bracket adapted to engage the studs to hold the bracket in horizontal position, a swivel head pivoted to the outer end of the bracket, a rod swivelly secured to said head, arms pivotally secured to said rod, lines movably attached to the arms, and means to hold the rod and arms housed within said bracket. 45

3. A clothes line support, comprising a hollow bracket, a supporting rod pivotally secured to said bracket, said rod being rotatable, a plurality of line supporting arms pivoted to said rod, means to hold the arms in folded position, and additional means to hold the rod and arm housed within the bracket. 55

In testimony whereof I have signed my name to this specification in the presence of two subscribing witnesses.

WILLIAM J. McCABE.
